United States Patent Office.

HENRY BRUGGEMAN, OF PETERSBURG, INDIANA.

Letters Patent No. 91,600, dated June 22, 1869.

IMPROVEMENT IN FANNING-MILLS.

The Schedule referred to in these Letters Patent and making part of the same.

To all whom it may concern:

Be it known that I, HENRY BRUGGEMAN, of Petersburg, in the county of Pike, and State of Indiana, have invented a new and useful Improvement in Fan-Mills; and I do hereby declare that the following is a full, clear, and exact description thereof, which will enable those skilled in the art to make and use the same, reference being had to the accompanying drawings, forming part of this specification, in which—

Figure 1 is a vertical longitudinal section of my improved machine.

Figure 2 is an end view of the same.

Similar letters of reference indicate corresponding parts.

My invention has for its object to improve the construction of fan-mills, so as to adapt them to the various purposes for which such a machine is required by a farmer, such as separating and cleaning grain, removing smut, &c.; and

It consists in the construction and combination of various parts, as hereinafter more fully described.

A is the frame of the machine.

B is the case.

C is the fan-shaft, which is pivoted to the frame A, and is operated in the ordinary manner.

D are the fans, which are made in parts, as shown in fig. 1, so that in cleaning small grains, which do not require so much wind as the larger and heavier grains, parts of the fans may be removed, to adjust the wind as may be required.

E is the shoe, the inner end of which is suspended from the frame A, by means of an eye-bolt, F.

The other end of the shoe E is suspended from the frame A by the adjustable irons G, the lower ends of which are connected with the sides of the shoe E, and the upper ends of which are connected to the frame A, by bolts or pins passing through one or the other of the holes in the irons G, and entering holes in the said frame A, so that the position of the shoe E may be adjusted as required for the particular work to be done.

H is the separating-box, which is stationarily attached to or formed in the inner part of the shoe E, immediately beneath the first groove in the said shoe.

In the bottom of the box H is formed a hole, through which the particles or fine seeds, that may enter the said box E, pass into the hose or flexible spout I, by which they are conducted to the floor, or into some suitable receptacle, without mixing with the grain upon the other sieves or screens.

By this means, and by using coarse or fine screens, according to the kind of grain to be operated upon, the operator may separate any desired grain.

The groove e' , of the shoe E, may be extended back, so that any screen or sieve now in use may be used in the mill, by pushing them back, and making them even with the box H.

The box H also serves to concentrate the wind and direct it more fully upon the grain, thus giving a greater cleaning power to the mill.

The middle screen, when placed in the groove e' , will detain the grain momentarily, allowing light substances, such as chaff, smut, &c., to be blown out.

For heavier substances, the said screen should be placed in the groove e'' or e''' .

The lower screen is adjusted in position by means of the set-screws J, upon the ends of which the said screen rests.

The plate K, which may be made of tin, wood, or other suitable material, and which is represented as being interposed between the said lower screen and the screws J, is provided with an upwardly-projecting flange, rising above the rear ends of said screen, which, when the rear end of the said screen is raised, prevents the grain or seed from being blown over.

L is a rubber, or other gum-elastic roller, the journals of which revolve in eye-bolts or other adjustable bearings, attached to the frame M, or to the top of the mill, and to which motion is given from the fan-shaft C, by bands passing around the said fan-shaft, and around the shaft of the roller L, and the length or tautness of which bands is regulated by the adjustable pulleys N, over which the said bands pass.

O is a sheet-metal concave or trough, adjustably suspended from the frame M, by the bolts and nuts P, so that the said concave may be moved nearer to or farther from the roller L, according to the size of the grain to be cleaned of smut.

As the grain passes through the concave O, the smut is crushed from the kernels of grain, without injuring said kernels, and while the grain escapes over the edge of the concave O, the smut passes through the holes formed in the said concave, and falls into the box H, from which it passes out of the mill.

The smut falls into the box H, just in the rear of the guard-plate Q, made of tin, or other suitable material, and placed upon the shoe E, as shown in fig. 1.

It should be observed that the smut-roller L should not be used until the light smut has all been blown from the grain.

I claim as new, and desire to secure by Letters Patent—

1. The smut-roller L, constructed as described, and perforated adjustable concave O, in combination with the shoe E and frame A of a fan-mill, substantially as herein shown and described, and for the purpose set forth.

2. Adjusting the lower screen of the shoe E by means of the set-screws J, substantially as herein shown and described.

3. The combination of the flanged plate K with the adjusting-screws J, and lower screen of the shoe E, of the fan-mill, substantially as herein shown and described, and for the purpose set forth.

HENRY BRUGGEMAN.
